(57) **CLAIM**

The ornamental design for a colander kit, as shown and described.

DESCRIPTION

FIG. 1 is a perspective view of a colander kit showing my new design, wherein the colander kit comprises a first colander, a second colander, a third colander and a handle; FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a perspective view of the first colander of the colander kit;

FIG. 9 is a top view thereof;

FIG. 10 is a bottom view thereof;

FIG. 11 is a front view thereof;

FIG. 12 is a rear view thereof;

FIG. 13 is a right side view thereof;

FIG. 14 is a left side view thereof;

FIG. 15 is a perspective view of the second colander of the colander kit, the third colander of the colander kit being identical to the second colander;

FIG. 16 is a top view thereof;

FIG. 17 is a bottom view thereof;

FIG. 18 is a right side view thereof;

FIG. 19 is a left side view thereof;

FIG. 20 is a front view thereof;

FIG. 21 is a rear view thereof;

FIG. 22 is a perspective view of the handle of the colander kit;

FIG. 23 is a top view thereof;

FIG. 24 is a bottom view thereof;

FIG. 25 is a front view thereof;

(Continued)

FIG. 26 is a rear view thereof;
FIG. 27 is a left side view thereof; and,
FIG. 28 is a right side view thereof.
